FLEXIBLE SWITCH FOR ROLLER CONVEYERS

Robert H. Metzgar, Grand Rapids, Mich., assignor to Metzgar Company, Inc., Grand Rapids, Mich., a corporation of Michigan

Application September 8, 1949, Serial No. 114,500

8 Claims. (Cl. 193—36)

1

In roller conveyors, conveyor switches are frequently desirable in order to be able to connect one conveyor line with either of two or more other conveyor lines at will. Thus some of the articles moving along the first conveyor may be passed away in one direction while others proceed in a different direction.

One of the most satisfactory types of conveyor switches has involved a flexible principle, the shifting of the switch being accomplished in part by a relative movement of each roller in the switch mechanism with respect to the preceding roller. Thus for straightway delivery the rollers would all be parallel while for delivery to one side of the same rollers would be arranged in a curve and would be properly disposed with their axes arranged radially about the center of the curve.

The present invention provides such a switch with a more simple structure than has heretofore been available for flexible switches having the high dependability of the present switch.

Additional objects and advantages of the invention will be apparent from the following description and from the drawings, in which:

Figure 1 is a view looking down on a switch chosen for illustration of this invention.

Fig. 2 is a side elevation of the switch seen in Fig. 1.

Fig. 3 is a bottom view of the switch shown in Fig. 1, rollers being omitted for simplicity.

Fig. 4 is a perspective view of the flexible blade which aligns the rollers.

Fig. 5 is a transverse vertical sectional view taken approximately on the line 5—5 of Fig. 2.

Fig. 6 is a similar view taken approximately on the line 6—6 of Fig. 2.

Although the law requires a full and exact description of at least one form of the invention, such as that which follows, it is, of course, the purpose of a patent to cover each new inventive concept therein no matter how it may later be disguised by variations in form or additions of further improvements; and the appended claims are intended to accomplish this purpose by particularly pointing out the parts, improvements or combinations in which the inventive concepts are found.

The invention has been illustrated as embodied in a switch for connecting conveyor A at will with conveyor B or conveyor C. Ordinarily the conveyor would slope downwardly from left to right so that articles delivered at higher points on conveyor A would roll down conveyor A and roll onto conveyor B or conveyor C, depending on the position of the switch. The switch is operated merely

by operating a lever 11. The lever 11 shifts the various shiftable roll units 12 between the position shown in full lines in Fig. 1 and a position in which the end roller unit is approximately parallel with fixed roller 13.

The switch unit includes a base formed mainly of horizontal beams 16 and 17 and bed plate 18. As seen best in Fig. 5, the beams 16 and 17 are formed of inwardly facing channel members. In the illustrated switch the beam 16 is straight, while the beam 17 is curved. However, in a three-way switch, designed to connect to a third conveyor by making a righthand curve, the beam 16 would be curved to the right as the beam 17 is curved to the left.

The plate 18 may be secured between the beams 16 and 17 in any desired manner. That at present preferred is to weld spacer blocks 21 to the inner faces of the beams as shown and to weld the plate 18 to the inner faces of blocks 21. This leaves openings 22 through which any debris from the traveling articles may drop in order to keep the bed 18 clear.

Although the beams 16 and 17 may be supported in any suitable manner, it is preferred that they are welded to connector beams 23 which are provided with connector brackets 24 for coupling to similar brackets on the conveyors A, B and C. Likewise, connector beams 26 are provided for coupling with the opposite sides of conveyors B and C.

Fixed rollers 13, 27 and 28 are carried by the various connector beams as illustrated, any conventional bearings being provided. The rollers 27 may conveniently be called receiving rollers and the rollers 13 and 28 delivery rollers.

The switching roller units 12 are constructed as seen best in Fig. 5. Thus each roller unit (two aligned rollers) is supported by a carriage or low U-shaped frame which may include a bottom channel piece 31 and the end channel pieces 32, each end channel piece being welded to the bottom piece 31. This carriage slides on plate 18. Extending between end pieces 32 is bolt 33. The bolt passes through the end pieces 32 and also through spacer or spanner tubes 34, between which is positioned a flexible band 36. Washers may be provided between the tubes 34 and the band 36, and likewise between the tubes 34 and the end pieces 32. The dimensions are such that the band 36 is tightly squeezed so that it is held rigidly perpendicular to the axis of the assembly. As seen best in Fig. 1, the band 36 extends through all of the shiftable switch rollers. As a matter of fact, it also extends to the end roll unit 37 which,

though resembling the shiftable roll units 12, is bolted to the bed plate 18 as by bolts 38 seen in dotted lines in Fig. 2.

The roller unit 38 at the shiftable end of the switch series is provided with pins or bolts 39 extending through the bed plate 18 but loose enough to ride freely in slot 41. A shift plate 42 is secured to the pins 39 below the bed plate 18 and is operated by shift lever 11. Thus as end roller 38 is shifted between the two illustrated positions, its angularity is correspondingly changed as the pins 39 follow slot 41. As this roll unit 38 shifts it shifts its end of the flexible band 36 accordingly and the band 36 in turn shifts the various intermediate roller units 12 so that these rollers assume a smooth curve, if the switch is in a deflected position. At the same time each roller is maintained in proper relative position with respect to the adjacent rollers.

The shift lever 11 may be pivoted to bed plate 18 by a bolt 44, preferably located where the center lines of conveyors B and C meet. Shift plate 42 may be similarly secured to shift lever 11 by a bolt 46, or it may be welded to it, since slot 41 is concentric with bolt 44.

The shift lever 11 may be operated manually by handle 47 or by a powered device which may be remotely controlled. For example, the powered device could be a fluid cylinder or an electromagnetic device.

As the rollers reach either extreme position, the lower flange 49 of the end piece 32 passes under the upper flange of the main beams 16 and 17, thus securely locking the roller units against excessive movement and ensuring that the proper curvature is assumed by the conveyor as a whole.

The beams 16 and 17 are preferably welded to the various end brackets 23 and 26, although the load is preferably transmitted mainly through the respective flanges. Thus the upper flange 51 of beam 16 may rest on the lower flanges 52 of brackets 23. In practice a thin spacer is positioned between these flanges so that the flanges 49 of the roller units 12 can pass under the flanges 51 quite easily.

It is often desirable to provide side guides along the outside of curves along the roller conveyors so that if the conveyed articles approach the curve at high speed they will be forced by the side guides to follow the curve. Without such side guides such speed might be enough to cause the articles to slide off the conveyor at the curve. In the case of a switch such as the present switch, the side guide for the curve cannot be in position all of the time because it would obstruct movement of the articles in the straight direction when desired. According to the present invention a side guide automatically shiftable with the switch is provided when desired.

The most practical way of accomplishing this is to provide independent side guide segments on the successive roller units 12. A few such segments have been shown in Figs. 1 and 2 and a cross-section of one of them is shown in Fig. 5. Here it is seen that each of the side guide segments or units may comprise a horizontal bar 56 curved outwardly at its ends so that articles will not catch on the ends. These bars may be carried by legs or rods 57 welded to the bars 56 and butt-welded to the upper flange 58 of end piece 32. One such segment may thus be carried by each end piece 32 along the side of the switch which is the outside of the switch in the curved position. In case the switch is designed to curve both to right and left, one of the side guide units

may be secured to each end piece 32 of the shiftable roller units.

Probably anyone skilled in the art would have no trouble selecting suitable materials. For such aid as it might give, the following data found satisfactory commercially are noted.

The flexible band 36 has been formed of $\frac{1}{8}$ " wide band steel 1" to $1\frac{1}{4}$ " wide, sometimes $1\frac{1}{2}$ ".

The bed plate 18 has been formed of 10 gauge hot rolled sheet steel for narrower conveyors ($11\frac{1}{2}$ "'), but heavier stock to at least $\frac{1}{4}$ " plate is contemplated for wider conveyors.

2" channel steel stock has been used for the beams 16 and 17, brackets 23, etc., end pieces 26 and bases 31. Steel tube stock of $\frac{3}{8}$ " O. D. and .032 wall thickness has been found satisfactory for spacer tubes 34 with $\frac{1}{16}$ " tie bolts 33.

Experience indicates that slot 41 may not be a true arc, but in any event it will be cut to accommodate the movement which guide bolts 39 are found to follow in a particular design to provide a radial disposition of the associated roller unit 38.

With the present design of switch the two end roller units 37 and 38 are intended to be in parallel relation to the adjacent fixed rollers. Alternatively they could be made to assume the same angularity with respect to adjacent fixed rollers as is assumed between adjacent shiftable rollers. This could be accomplished by a special shaping of slot 41 and by permitting one or both ends of the roller unit 37 to slide a limited amount under the influence of flexible band 36.

Although wide rollers have been shown in the drawings, narrow rollers, more commonly called wheels, could be used instead. In that event the bearings for the wheels would be separated by a series of spacer or spanner tubes, the flexible band 36 being clamped at the center within this series in much the same manner as is now illustrated. At present it is contemplated that in each roller unit 12 there would be a wheel at each end, a wheel adjacent the flexible band 36 and a wheel at an intermediate position on each side.

In the illustrated form of the invention the bearing units do not need to be spaced apart by the spanner tubes 34 because they are spaced apart by the roller cylinders or jackets with which the bearing wheels have a press fit.

The conveyor may be supported in any suitable manner. For example, cross braces 58 may be welded to the brackets 23 and 26 to rest on the cross members of tripod supports.

Each conveyor section is preferably coupled to an adjacent conveyor section by means of upwardly extending pins 61 rigidly associated with one conveyor section and extending up into a socket or eye 62 of the adjacent conveyor section. This provides a firm coupling. In fact, it is even practical to place two adjacent conveyor sections at a slight angle with respect to one another by using the coupling at only one side, this coupling nevertheless providing a firm relationship between the two conveyor sections.

Although the switch unit illustrated will connect with a conveyor extending away at 45 degrees from the entrance conveyor, it is apparent that a fixed curved conveyor section could be connected to the switch to deliver to a conveyor extending away at any angle. It is particularly common to use a 45 degree curve to thus connect to a conveyor extending at 90 degrees from the entrance conveyor.

Any suitable means may be provided for holding the switch in either position. For example,

operating lever 11 may engage one or the other of latch lugs 66 (Fig. 3), being urged toward plate 18 by spring 67.

I claim:

1. A flexible conveyor including a relatively fixed roller unit, a controlled roller unit, a plurality of intermediate roller units between the two, and a flat flexible band of stiff resilient material connecting the intermediate roller units with each other and with the relatively fixed and controlled roller units, said band extending through the axes of the roller units at approximately a mid point in the length of each roller unit.

2. A flexible conveyor including a relatively fixed roller unit, a controlled roller unit, a plurality of intermediate roller units between the two, and a flat flexible band of stiff resilient material connecting the intermediate roller units with each other and with the relatively fixed and controlled roller units, said band extending through the axes of the roller units at approximately a mid point in the length of each roller unit, and each roller unit being secured to the band in perpendicular relation thereto.

3. A flexible conveyor including a relatively fixed roller unit, a controlled roller unit, a plurality of intermediate roller units between the two, and a flat flexible band of stiff resilient material connecting the intermediate roller units with each other and with the relatively fixed and controlled roller units, said band extending through the axes of the roller units at approximately a mid point in the length of each roller unit, each of the roller units including a tie bolt and a plurality of spacer tubes strung on said tie bolt and drawn toward one another by said tie bolt with said bend clamped therebetween to hold the roller unit perpendicular to the face of the band, and roller means carried by said tie bolt, the tie bolt serving as an axle for the roller means.

4. A flexible conveyor including a relatively fixed roller unit, a controlled roller unit, a plurality of intermediate roller units between the two, and a flat flexible band of stiff resilient material connecting the intermediate roller units with each other and with the relatively fixed and controlled roller units, said band extending through the axes of the roller units at approximately a mid point in the length of each roller unit, each roller unit being secured to the band in perpendicular relation thereto, and a slab-like supporting surface on which said roller units, and through them the band, are slidably supported.

5. A flexible conveyor including a relatively fixed roller unit, a controlled roller unit, a plurality of intermediate roller units between the two, a flat flexible band of stiff resilient material connecting the intermediate roller units with each other and with the relatively fixed and controlled roller units, said band extending through the axes of the roller units at approximately a mid point in the length of each roller unit, each roller unit being secured to the band in perpendicular relation thereto, a slab-like supporting surface on which said roller units, and through them the band, are slidably supported, and a curved beam supporting the supporting surface and limiting the shifting movement of

the intermediate roller units, whereby the series of intermediate roller units is wrapped about the beam to form a conveyor corresponding to its curvature.

6. A flexible conveyor including a relatively fixed roller unit, a controlled roller unit, a plurality of intermediate roller units between the two, a flat flexible band of stiff resilient material connecting the intermediate roller units with each other and with the relatively fixed and controlled roller units, said band extending through the axes of the roller units at approximately a mid point in the length of each roller unit, each roller unit being secured to the band in perpendicular relation thereto, and means for limiting the movement of the intermediate rollers in one direction to conform all of said shiftable rollers to a uniform curve whereby the curve is spread through the entire series of intermediate rollers.

7. A flexible conveyor including a relatively fixed roller unit, a controlled roller unit, a plurality of intermediate roller units between the two, a flat flexible band of stiff resilient material connecting the intermediate roller units with each other and with the relatively fixed and controlled roller units, said band extending through the axes of the roller units at approximately a mid point in the length of each roller unit, each roller unit being secured to the band in perpendicular relation thereto, a slab-like supporting surface on which said roller units, and through them the band, are slidably supported, and a curved beam supporting the supporting surface and limiting the shifting movement of the intermediate roller units, whereby the series of intermediate roller units is wrapped about the beam to form a conveyor corresponding to its curvature, said beam including a flange extending toward said roller units and said intermediate roller units each including a flange which slips under the said flange of said beam as the roller unit approaches the beam.

8. A flexible conveyor including a relatively fixed roller unit, a controlled roller unit, a plurality of intermediate roller units between the two, a flat flexible band of stiff resilient material connecting the intermediate roller units with each other and with the relatively fixed and controlled roller units, said band extending through the axes of the roller units at approximately a mid point in the length of each roller unit, each roller unit being secured to the band in perpendicular relation thereto, and means varying the angular disposition of the controlled roller unit and, through it, of the adjacent part of the band as they are shifted.

ROBERT H. METZGAR.
